CATALYTIC ISOMERIZATION OF
ISOHEPTANES TO TRIPTANE

Jacob D. Kemp, San Francisco, and Arthur E. Stickland, Berkeley, Calif., assignors to California Research Corporation, San Francisco, Calif., a corporation of Delaware

Application January 22, 1946, Serial No. 642,604

4 Claims. (Cl. 260—683.5)

1

The present invention relates to the production of triptane (2,2,3-trimethylbutane) and pertains more particularly to a selective isomerization process for obtaining triptane from isoheptanes, such as methylhexanes and dimethylpentanes.

Triptane is a highly desirable fuel, since its highly branched structure gives it super-fuel characteristics exceeding that of iso-octane (2,2,4-trimethylpentane). In view of the difficulty in making it, triptane has for some time been somewhat of a laboratory curiosity. More recently, due to the war pressure and demands for better aviation fuels, triptane has been made by processes which involve expensive intermediates such as Grignard reagents. Triptane made by such processes and the like, or other methods wherein only small amounts of triptane are obtained, is ordinarily too expensive for general use.

It is therefore an object of the present invention to provide an improved method of producing triptane, whereby it can be commercially obtained in large yields from isoheptane without the use of expensive intermediates or processes.

It is another object of this invention to provide a process for selectively isomerizing isoheptanes, such as methylhexanes and dimethylpentanes, to triptane without the formation of excessive amounts of side reaction products, whereby triptane is relatively cheaply produced to permit its general use.

It is a further object to provide a method of obtaining a product containing a high concentration of triptane, wherein the side reaction products obtained therewith are valuable components of internal combustion engine fuels such as aviation gasoline.

Further objects and advantages of the present invention reside in special combinations of method steps, conditions and the like, as will be readily apparent from the following description of a preferred embodiment taken in reference to the drawing, which is a schematic flow diagram of one preferred embodiment of this invention.

In attaining the above objects of the present invention, isoheptanes, such as methylhexanes and dimethylpentanes, are selectively isomerized to triptane under rather specific conditions. Thus, the isoheptanes in the presence of a substantial excess of an n-paraffin, e. g., propane, in liquid form, is subjected to the action of certain liquid mixtures of hydrofluoric acid and boron trifluoride at a relatively low temperature. It is a special feature of the present invention

2

to control the catalytic activity of the liquid HF-BF₃ mixtures within relatively narrow limits by maintaining the BF₃ content at about 5-25% and preferably 13-19% by weight in the liquid mixture. By means of such a catalyst in combination with the other conditions set forth, a high ultimate conversion to triptane without excessive yields of side reaction or degradation products is obtained, whereas other catalysts are generally unsuitable for the present specific isoheptane isomerization for various reasons, such as low conversions, substantially complete inactivity at the desired low temperatures, excessive formation of degradation products—usually of the least useful type—such as permanent gases, e. g., methane and ethane, high catalyst consumption and cost, etc.

The isoheptanes—methylhexanes and dimethylpentanes—employed as starting materials are preferably substantially pure (i. e., above 90% concentration), although when combined with suitable n-paraffins, petroleum fractions containing lower percentages, e. g., 50%, of isoheptanes may be used. Ordinarily the isoheptane feed stock contains at least 65% by volume of methylhexanes and dimethylpentanes. As obtained from most sources, the isoheptanes are predominantly methylhexanes. Such is the case when normal heptane is isomerized to isoheptanes under optimum conditions for isoheptane formation without excessive loss to side reactions. For most convenient operation, the hydrocarbon feed material is freed of water, sulfur compounds, nitrogen bases, and other agents having deleterious action on the catalyst or imposing difficulties in catalyst regeneration.

It is a special feature of the present combination of isomerization conditions to employ a large excess of an n-paraffin in liquid form, such paraffin being soluble in the isoheptane. Other materials, such as carbon dioxide, nitrogen, etc., which have been used as gaseous additives in some isomerization processes for the purpose of imposing a gas pressure on the system, are not soluble in the present isoheptanes to an appreciable extent and are not satisfactory for the purpose of this process. Generally suitable for use in the present isoheptane isomerization process are the hydrocarbons: ethane, propane, normal butane, normal pentane, normal hexane, normal heptane, and mixtures thereof in liquid form. Generally, the lower molecular weight hydrocarbons are most desirable, since lower isomerization temperatures or lower catalytic activity with attendant lowered conversions are

usually necessary as the number of carbon atoms in the n-paraffin increases. Propane is especially preferred, since greater conversion and less side reactions as well as ease of operation are obtainable therewith in most instances. Normal paraffinic hydrocarbons above n-heptane may sometimes be used; but only those are suitable which do not substantially react at the required temperature necessary for satisfactory isomerization of the isoheptane. When propane-containing mixtures of n-paraffins, such as propane and butane, are used, it is usually preferable that the propane form the major part of the mixture. Such mixtures are sometimes more advantageous than a single n-paraffin.

The n-paraffin, especially propane, is employed in substantial excess of the rest of the hydrocarbon mixture charged to the isomerization zone. Thus, the ratio of n-paraffin to isoheptanes is generally 2-20:1, and preferably 8-12:1 by volume, i.e., the n-paraffins constitute 50-85% and preferably about 75% of the reaction mixture.

The temperature employed in the isomerization zone is relatively low, of the order of room temperature and below. In general, the temperature is below that at which substantial reaction of a n-paraffin occurs but sufficient to obtain satisfactory isomerization of the isoheptanes. Preferably, a temperature of 25-75° F. and especially about 50° F. is employed. Above this range, the amount of triptane produced rapidly decreases with an attendant increase in the amount of side reactions and/or degradation products formed, while below this range the conversion to triptane is unsatisfactory.

Pressure, as such, is not especially important in the present isomerization process and high pressures do not appreciably increase or decrease the isomerization to triptane. Generally, the pressure is correlated with the nature of the n-paraffin and the BF_3 content in the liquid catalyst; that is, sufficient pressure is employed to maintain the desired concentration of BF_3 in the liquid catalyst and the normal paraffin in liquid form. The partial pressure of BF_3 in the isomerization zone is particularly important since it controls the amount of BF_3 in the active liquid catalyst mixture. A special advantage of the present invention resides in the ease of maintaining the desired narrow range of catalyst activity by means of the BF_3 partial pressure, since a relatively large increase in the partial pressure of BF_3 has a relatively small effect on the BF_3 content of the liquid catalyst. Thus, the BF_3 partial pressure provides an excellent way of controlling the BF_3 content in the liquid catalyst within the desired narrow range. For example, a partial pressure of BF_3 of about 30 to 275 lbs./sq. in. gives a BF_3 content of about 5 to 25% at 50° F. in the liquid catalyst mixture. As indicated, the total amount of BF_3 introduced into the isomerization reactor will depend upon the equilibrium pressure of BF_3 at the temperature employed, the ratio of liquid catalyst to hydrocarbon and upon the gas phase above the liquid mixture. Thus, the lower the amount of free space in the isomerization zone the lower the total amount of BF_3 that is required. For example, in an isomerization reactor there was contained 2950 cc. of gas space at 120° F. and 1850 cc. of liquid at 50° F. under a total absolute pressure of about 225 lbs./sq. in. A total of 150 gms. of BF_3 was charged, of which 76.6 gms. was in the gas phase, 45.6 gms. was in the liquid

catalyst phase and 27.8 gms. was in the hydrocarbon phase. The remainder of the liquid catalyst consisted of 215 gms. of HF. The partial pressure of BF_3 was 165 lbs./sq. in. absolute at 120° F. The liquid catalyst then contained 17.5 weight per cent of BF_3 .

Although only relatively small amounts of side reaction products are formed in the present isomerization process as compared to the amount of degradation products obtained by using other conditions of temperature, catalyst, diluent, etc., it is particularly important and a special feature of the present invention to recycle side reaction products or like materials from extraneous sources to the isomerization zone. The side reaction products, which include butanes, pentanes and hexanes, are employed in substantial amount, such as 0.5 to 3 parts of side reaction products to 1 part of isoheptane. Preferably, the ratio is about 1:1. However, in any event the side reaction products are employed in amounts less than about 50% of the n-paraffins, such as propane. In some instances, it is desirable to introduce also into the isomerization zone hydrogen and/or naphthenes, such as cyclohexanes, cyclohexanes, etc.

The ratio of catalyst mixture to isoheptanes depends, at least in part, upon the activity of the liquid catalyst mixture, the amount of relatively inert n-paraffin and the temperature employed. A large enough amount of liquid catalyst is employed to yield sufficient active catalyst surface to obtain the desired isomerization in a relatively short time. A constant renewal of the active catalyst surface available to the isoheptanes is most desirable in preventing side reactions. The liquid catalyst may form 5-95% of the total liquid mixture, including the isoheptanes, n-paraffin, etc. When using the preferred amounts and proportions of hydrocarbons, i.e., around the middle of the ranges given, the ratio of catalyst mixture to isoheptane may be from about 0.2 to 2.0 by volume and preferably is in the vicinity of 1.0.

The contact time between the isoheptane and liquid HF, BF_3 catalyst at isomerization conditions is preferably relatively short, such as 10-30 minutes, more or less, depending in part upon the nature of the isoheptanes charged. Thus, when the isoheptanes are predominantly methylhexanes, a longer contact time is employed than is used with dimethylpentanes as the predominant isoheptanes in the isomerization charge. Likewise, with lower catalyst activities (i.e., lower BF_3 content in liquid catalyst) and lower temperatures, longer contact times are usually required. Further, for best results as are usually obtained in shortest contact time, it is especially important to use thorough agitation to obtain sufficient contact between the catalyst and the isoheptanes in the isomerization zone whereby the desired isomerization is obtained with a minimum of degradation in the side reaction products. Less preferably, longer contact time may sometimes be tolerated when only a coarse dispersion of catalyst throughout the hydrocarbon feed material is achieved.

Depending upon whether methylhexanes or dimethylpentanes predominate in the isoheptane charge and the conditions employed, the conversion per pass to triptane will range upwards from 15% by volume or more. Under the more preferred conditions, ultimate conversion above about 50% triptane will be obtained along with

production of other valuable gasoline components.

The mixture resulting from the above isomerization is freed of HF, BF_3 catalyst, n-paraffin, e. g., propane, and lower boiling side reaction products, each of which may be in whole or in part recycled, discarded or regenerated, as is applicable. The remaining crude triptane concentrate containing methylheptanes, dimethylpentanes and a small amount of hydrocarbons heavier than heptanes, usually are separated further to obtain a more concentrated triptane fraction by any suitable means, such as distillation, fractional crystallization, extraction or distillation with selective solvents, etc., or combinations thereof. Most desirably, the crude triptane concentrate is subjected to fractional distillation wherein a mixture of triptane and 2, 4-dimethylpentane are separated from methylhexanes and 2,3-dimethylpentane, which latter mixture may be recycled to the isomerization. Preferably the mixture of triptane and 2,4-dimethylpentane is further separated by solvent distillation, i. e., extractive distillation, with a selective solvent such as dialkylphthalates, e. g., diethylphthalate, etc., nitroaromatics, e. g., nitrobenzene, nitrotoluene, etc., aromatic amines, e. g., aniline, etc., ketones, anhydrides, and the like.

It is apparent that the present process and any step thereof can be carried out either continuously or batchwise, or combinations of batchwise and continuous treatments may be used. In the isomerization any suitable apparatus providing thorough contact between the catalyst mixture, the various ingredients of the feed material, including recycle products and added n-paraffins, may be employed. For example, combinations of mechanically driven agitators, such as turbo mixers with settlers, used either singly or in series or parallel, packed columns adapted from concurrent or countercurrent flow, or coil reactors which may contain mixing jet nozzles, or the like, may be used. Since it is particularly important in the present process to attain thorough contact between the liquid HF, BF_3 catalyst mixture and isoheptanes, it is preferred to use contacting devices, such as turbo mixers or other relatively high speed agitator and baffle arrangements wherein the catalyst is quickly and finely dispersed throughout the hydrocarbon charge.

The material forming the isomerization reactor, or reactors, and other apparatus, especially that which is in contact with the HF, BF_3 catalyst, is ordinarily substantially inert, such as Monel, nickel, Hastalloy, etc., so that no reaction of HF and/or BF_3 takes place with the apparatus material to form substances inhibiting the isomerization reaction or to form excessive amounts of contaminants. Many suitable types of apparatus can be constructed readily by one skilled in the art, but the invention is now further illustrated and may be better understood by reference to the schematic drawing showing one preferred embodiment of the present invention and wherein, for the sake of simplicity and clarity, there have been omitted certain details, such as pumps, valves, pressuring means, coolers, heat exchangers, reflux systems, etc.

In an embodiment of the preferred continuous process flow of the present invention as shown in the drawing, the feed isoheptane comprising mainly either methylhexanes and/or dimethylpentanes are introduced into isomerization reactor 10 through line 11 along with an n-paraffin, e. g., propane, via lines 12 and 13, recycled ma-

terial via lines 13 and 14, and HF, BF_3 catalyst mixture through line 15. The reaction mixture in the isomerization reactor 10 is constituted in accordance with the ranges given hereinabove as obtained from added or recycled materials. For example, the reaction mixture may contain 1 volume of the isoheptanes: methylhexanes and/or dimethylpentanes, 8 volumes of propane, 1 volume of side reaction products including butanes, pentanes and hexanes, and 1.5 volumes of a liquid HF, BF_3 catalyst mixture containing about 13-19% by weight of BF_3 . This reaction mixture is thoroughly agitated within the isomerization reactor 10 at about 50° F. and under about 105-175 lbs./sq. in. partial pressure of BF_3 , allowing about 15 minutes contact time. The isomerization product mixture including HF, BR_3 and hydrocarbon leaves the isomerization reactor 10 and passes to line 18 into settler 19, wherein a separation into a hydrocarbon phase and a catalyst phase takes place. The catalyst phase may be in whole or in part either recycled through lines 20 and 15 to the isomerization reactor 10 or passed to disposal line 21 for rejection of suitable regeneration. Fresh catalyst or any component thereof as required to maintain the quantity and ratio of HF to BF_3 in the liquid catalyst, may be added to the isomerization system through line 22.

The hydrocarbon phase contains triptane, dimethylpentanes, methylhexanes, some catalyst materials and a small amount of side reaction products such as butanes, pentanes and hexanes. This hydrocarbon phase passes through line 25 to a suitable separator, such as depropanizer 26 wherein propane and lower boiling material including HF and BF_3 are removed for recycle through lines 27 and 13 to the isomerization reactor 10. Material boiling higher than propane passes from depropanizer 26 to line 29 to a further separator, such as dehexanizer 30, for separation into two fractions: one containing materials boiling below the heptanes, such as a small amount of side reaction products, including butanes, pentanes and hexanes, and a second fraction containing the heptanes and small amounts of higher boiling materials. The lower boiling fraction discharges from dehexanizer 30 through line 31 from whence it may be recycled to the isomerization reactor 10 through lines 13 and 11 or to other disposal through line 32, or both. In general, although the side reaction product hydrocarbons together with the mixture of propane, HF and BF_3 , may be recycled to the isomerization reactor 10, the separation between the HF, BF_3 mixture and the hydrocarbons may be effected in any suitable manner whereby all or part of each of the separated portions may be recycled or disposed of in other ways. Thus, part of the HF, BF_3 mixture may pass to a suitable catalyst regeneration, and the hydrocarbons, other than that required for recycle, may be used for blending in gasoline, since these hydrocarbons are valuable gasoline components.

The higher boiling heptane fraction leaving the dehexanizer 30 passes through line 34 into heptane fractionator 35. Therein the heptane fraction is separated into a lower boiling crude triptane concentrate containing 2,4-dimethylpentane, and a higher boiling fraction containing mainly 2,3-dimethylpentane and methylhexanes. The latter fraction or bottoms may be withdrawn through line 36 and recycled to isomerization reactor 10 through lines 14 and 11. If desired, all, or preferably only part, of the bottoms may be further separated by passing

through line 37 to rerun still 40 wherein small amounts of heavier material boiling above heptanes, such as octane, etc., may be removed through line 41, the heptanes passing through line 42 to recycle line 14. The heptane fractionator 35 is preferably a distillation column, or columns, either packed, tray, or bubble cap type, of a sufficient number of theoretical plates to effect a separation between the two desired isooctane fractions. Thus, a top temperature equivalent to about 178-185° F. at atmospheric pressure may be maintained. The almost negligible amount of 2,2-dimethylpentane and 3,3-dimethylpentane formed will be found in the triptane concentrate and in the heptane fractionator bottoms, respectively. It is one of the advantages of the present invention that the use of a liquid n-paraffin, particularly propane, in the isomerization reactor prevents or minimizes the formation of 2,2-dimethylpentane and 3,3-dimethylpentane, thereby permitting an easier separation between triptane and 2,4-dimethylpentane on the one hand and the remaining isoheptanes on the other hand; in contradistinction, when isobutane instead of propane is used as the principal diluent in the isomerization zone appreciable amounts of these neo carbon atom dimethylpentanes are formed under conditions for production of comparable amounts of triptane. This is illustrated by the heptane analyses in the following table:

	A	B	C
Principal diluent	Propane	Propane	Isobutane
Vol. per cent-diluent in feed	75	25	75
Contact time, min.	15	15	90
Temperature, ° F.	50	50	50
Infra-red analysis, heptane fraction, vol. per cent:			
Triptane	17.2	16.5	11.8
2,2-dimethylpentane	nil	0.8	5.5
3,3-dimethylpentane	nil	1.3	9.7
2,3-dimethylpentane	12.4	11.2	10.2
2,4-dimethylpentane	25.4	23.8	20.5
2-methylhexane	27.8	28.9	27.1
3-methylhexane	17.2	17.5	15.2
Ethylpentane	nil	nil	nil
Normal-heptane	nil	nil	nil

The triptane concentrate leaving heptane fractionator 35 through line 45 contains about 40% or more triptane and the remainder almost entirely 2,4-dimethylpentane. Although this triptane concentrate has a fairly high octane number and may thus be used as such for aviation fuel, it is more preferable to separate further to get at least 80% and most desirably substantially pure (i. e., above 90%) triptane. Due to the closeness in boiling point of triptane and 2,4-dimethylpentane, fractional distillation cannot ordinarily be used. A suitable method of separation involves the use of selective solvents. Thus the triptane concentrate may be passed through line 45 to an extractive distillation system. For example, in the schematic extractive distillation system shown, triptane concentrate is introduced into the middle portion of a column 50 such as of packed, tray or other suitable type, while a selective solvent such as diethylphthalate is introduced through line 51 into the upper portion thereof. Substantially all or at least a principal amount of the 2,4-dimethylpentane together with any 2,2-dimethylpentane is taken overhead through line 52 and recycled through line 14 and 11 to isomerization reactor 10. A mixture of triptane and solvent along with a small amount of 2,4-dimethylpentane is withdrawn from the bottom portion of the column 50 and passed

through line 53 to a suitable separator or fractionator 55, wherein triptane is removed from the solvent and passes out through line 56. The remaining solvent is recycled through line 51 to distillation column 50.

The triptane thus obtained may be of about 80% concentration but is usually in the vicinity of 90% or above. If further purification is required it is usually suitable to employ fractional crystallization whereby triptane may be readily crystallized from the mixture.

By means of the above described preferred process flow of the present invention high yields can be obtained from isoheptane by isomerization. The over-all conversion to triptane is in the vicinity of 50% or higher, the remainder consisting mainly of valuable gasoline components. Thus, for the first time, triptane is produced in good yields by isomerization.

As illustrative of the above described process the following example is given:

Isoheptane isomerization

Conditions:

Temperature ----- 50° F.
Contact time ----- 15 min.
Catalyst (liquid) ----- 19% BF_3 , 81% HF
Ratio catalyst to total hydrocarbons ----- 14:86 by vol.

Charge to reactor:

1000 bbls/day isoheptanes consisting of about 80% methylhexanes and the remainder principally dimethylpentanes
35 2440 bbls/day isoheptanes recycled
18400 bbls/day propane recycled
1225 bbls/day isobutane recycled
980 bbls/day pentanes recycled
980 bbls/day hexanes recycled.

Product from reactor:

18400 bbls/day propane
45 2440 bbls/day isoheptanes (other than triptane)
500 bbls/day triptane
1381 bbls/day isobutane
1046 bbls/day pentanes
1055 bbls/day hexanes
29 bbls/day heavy oils from acid phase
192 bbls/day octanes and heavier.

Although the above described process flow represents an illustration of a preferred embodiment of this invention, it will be readily appreciated that many modifications and changes may be made without departing from the spirit and scope of the present invention as is defined by the claims hereinbelow. Thus, instead of using the preferred propane as the principal diluent in the isomerization, other n-paraffins may be employed, in which case the depropanizer 26 will not ordinarily be operated at least as such. In the event n-heptane is employed in the isomerization, the depropanizer 26 may be omitted and the hydrocarbon phase from settler 19 passed directly into dehexanizer 30, in which case it is preferable to separate by suitable means the dehexanizer overhead material into HF, BF_3 mixture and hydrocarbons, for example, in order to obtain more controlled recycle operation.

In the above described triptane production process it may sometimes be advisable, instead of separating the triptane concentrate by extractive distillation, to subject this mixture of triptane and 2,4-dimethylpentane to a selective isomeri-

zation process whereby the latter is isomerized to 2,3-dimethylpentane and methylhexanes, which are relatively easily separated by fractional distillation from triptane. For example, 1 part of a triptane concentrate is vigorously agitated for a short time (about 15 minutes) at approximately 50° F. with about 0.2 to 2.0 parts by weight of an isomerization catalyst consisting of 0.1 to 5%, preferably about 1%, by weight of BF_3 in the liquid catalyst and the remainder HF. The hydrocarbon phase separated from the liquid catalyst is fractionally distilled to remove the 2,3-dimethylpentane and methylhexanes which may be recycled to the isomerization reactor 10. The low boiling triptane concentrate thereby obtained contains less than half as much 2,4-dimethylpentane as prior to the selective isomerization process above described. Thus, for example, a triptane concentrate containing about 20% 2,4-dimethylpentane when so treated yields a new triptane fraction containing less than 10% and usually below 5% 2,4-dimethylpentane.

As pointed out or indicated hereinabove, the process of the present invention provides an especially advantageous method of producing triptane in large yields at relatively low cost. Further, practical contact times are obtainable in the operation in liquid phase at relatively low temperatures. The amount of side reaction is small and high concentration of triptane is obtained due at least in part to both specific isomerization to triptane compared to isomerization to other neo-carbon atom heptanes and favorable thermodynamic equilibrium. This is made possible by the use of liquid n-paraffin, especially propane, as the diluent, whereby the catalyst, of any given composition which is correlated with a given activity level, has a maximum activity since propane and the like do not occupy active catalyst centers on the catalyst surface as occurs when other agents are used as the principal diluents.

We claim:

1. A method for the production of triptane by the isomerization of isoheptane concentrates comprised of a major portion of the methyl hexanes and a minor portion of the dimethyl pentanes which comprises intimately contacting a mixture of one volume of isoheptane concentrate, 2-20 volumes of liquid propane and 0.5-3 volumes of hydrocarbons obtained as side-reaction products in said isomerization with 0.2-2 volumes of a liquid isomerization catalyst mixture containing about 5-25% by weight of BF_3 and the remainder HF at a temperature of 25-75° F. for about 10-30 minutes, separating from the reaction product mixture an isoheptane concentrate containing substantially all of the triptane formed in the course of the reaction, separating from the isoheptane product concentrate a triptane concentrate containing 2,4-trimethylpentane as the principal diluent, subjecting the triptane concentrate to extractive distillation in the presence of diethylphthalate as a selective solvent, recovering from the extractive distillation step a mixture of triptane and diethylphthalate, and separating therefrom a triptane concentrate containing at least 80% triptane.

2. A method for the production of triptane by the isomerization of isoheptane concentrate comprised of a major portion of the methyl hexanes and a minor portion of the dimethyl

pentanes which comprises intimately contacting one volume of isoheptane concentrate, 6-12 volumes of liquid propane, and 0.5-3 volumes of hydrocarbons obtained as side reaction products in said isomerization with 0.2-2 volumes of a liquid isomerization catalyst mixture containing 5-25% by weight of BF_3 and the remainder HF at a temperature of 25-75° F. for about 10-30 minutes, separating from the reaction product mixture an isoheptane concentrate containing substantially all of the triptane formed in the course of the reaction, separating from the reaction product isoheptane concentrate, a triptane concentrate containing 2,4-dimethylpentane as the principal diluent, vigorously agitating one volume of the triptane concentrate with 0.2-2 volumes of a liquid isomerization catalyst mixture containing 0.1-5% by weight of BF_3 and the remainder HF for a short period of time at about 50° F., whereby the 2,4-dimethylpentane is selectively isomerized to methyl hexanes and 2,3-dimethylpentane and thereafter separating triptane from the reaction product by fractional distillation.

25 3. In a process for the production of triptane by the catalytic isomerization of isoheptanes the improved method which comprises contacting a liquid feed consisting predominantly of methyl hexanes and dimethyl pentanes with a liquid isomerization catalyst consisting of HF and BF_3 and containing about 5-25% by weight of BF_3 at a temperature of 25° F. to 75° F., effecting said catalyst contacting step in the presence of 6-12 volumes of liquid propane per volume of 30 feed whereby the formation of undesired side reaction products especially 2,2 and 3,3 dimethyl pentane is substantially reduced.

35 4. A method for the production of triptane by selective isomerization of isoheptanes which 40 comprises intimately contacting one volume of a liquid feed consisting predominantly of methyl hexanes and dimethyl pentanes with 0.2 to 2 volumes of a liquid isomerization catalyst consisting of HF and BF_3 and containing 5-25% 45 by weight of BF_3 at 40-60° F. for a period of 10 to 30 minutes, effecting said catalyst contacting step in the presence of about 6 to 12 volumes of liquid propane whereby the formation of 2,2 and 3,3 dimethyl pentane is substantially reduced.
